CLAIM

I claim the ornamental design for a garment lapel and button holder, as shown.

DESCRIPTION

FIG. 1 is a front elevational view of the garment lapel and button holder showing my new design;

FIG. 2 is a rear elevational view thereof;

FIG. 3 is a top plan view thereof;

FIG. 4 is a bottom plan view thereof;

FIG. 5 is a left side elevational view thereof; and,

FIG. 6 is a right side elevational view thereof.
